UNITED STATES PATENT OFFICE.

GEORGE S. MARSHALL, OF ST. LOUIS, MISSOURI, ASSIGNOR TO THE MISSOURI RAILWAY EQUIPMENT COMPANY, OF SAME PLACE.

TIMBER-POCKET.

SPECIFICATION forming part of Letters Patent No. 607,867, dated July 26, 1898.

Application filed December 10, 1897. Serial No. 661,410. (No model.)

To all whom it may concern:

Be it known that I, GEORGE S. MARSHALL, a citizen of the United States, residing at the city of St. Louis, State of Missouri, have invented a certain new and useful Improvement in Timber-Pockets, of which the following is a full, clear, and exact description, such as will enable others skilled in the art to which it appertains to make and use the same, reference being had to the accompanying drawings, forming part of this specification, in which—

Figure 1 is a view representing a portion of the skeleton framing of a car, showing the application of my improved timber-pocket, said view being taken on line 1 1, Fig. 2, looking in the direction of the arrows. Fig. 2 is a side elevational view of the same. Fig. 3 is a plan view of my improved timber-pocket. Fig. 4 is a sectional view through the same on line 4 4, Fig. 3. Fig. 5 is a side elevational view of the same. Fig. 6 is a bottom plan view showing my improved pocket provided with a lateral wing. Fig. 7 is a side elevational view of the same. Fig. 8 is a similar view as seen from the other side. Fig. 9 is a side elevational view of my improved pocket when used as a carline-support. Fig. 10 is a plan view of the same. Fig. 11 is a plan view of a modified form of pocket. Fig. 12 is an edge view of the same. Fig. 13 is an edge view of the pocket when used as an end-plate support, and Fig. 14 is a plan view of the same.

This invention relates to a new and useful improvement in timber-pockets, the object being to provide a metallic pocket for receiving the end of a timber, whereby the same may be firmly secured in position against another timber without mortising the latter.

The special features of this invention reside in the novel construction of the pocket, as will hereinafter be described, and afterward pointed out in the claims.

In the drawings I have shown a portion of the skeleton timbers of a car in connection with which my improved pocket is illustrated; but it will be obvious that there are many other uses to which my pocket could be put without in the least departing from the principle of my invention.

In the drawings, A indicates the end plate, B the side plate, C the end posts, D the side posts, and E the carlines, all of said parts being common and well known in car construction.

F indicates my improved pocket as an entirety, which, as shown in detail in Figs. 3, 4, and 5, comprises a base-plate f and side walls f' , f^2 , and f^3 . The base-plate f has a hollow boss f^4 and a stud or dowel pin f^5 , extending outwardly therefrom, said boss and stud fitting in suitable recesses or holes in one of the timbers when the pocket is applied.

f^6 indicates an opening in the base-wall f for the passage of a truss-rod should one be used and it is desired to have the same countersunk or flush with the side face of the timber whose end is received by the pocket.

The edges of the walls f' and f^3 are formed with guideways, in which is received a slide f^7 , said slide being tapered, as shown in Fig. 4, and also provided with an opening or hole f^8 for the passage of a wood-screw, by which the slide is secured to the timber whose end is received by the pocket.

As will be seen by reference to Fig. 4, the inner faces of the grooves in the walls f' and f^3 for the slide f^7 are practically parallel with the wall f^2 , while the outer faces of said grooves incline toward the base-plate f . The object of this is to cause the slide f^7 to move inwardly as it is driven home, so as to tightly crowd and bind the end of the timber in the pocket to prevent lateral movement of said timber, after which the wood-screw is introduced to secure the slide to the timber and in position.

f^9 indicates a wing against which the end of a diagonal post may abut, as shown in Figs. 1, 2, 6, 7, and 8. This wing or lateral plate is also provided with a dowel f^{10} , as shown, if desired.

If desired, a removable key f^{11} may take the place of the wall f^2 , so that the timber whose end is to be inserted in the pocket may be placed in position from either side.

The use of my improved timber-pocket and its application can be readily understood from the drawings. I will state, however, that in practice I prefer to bore the timber

on which the pocket is to be secured with holes of sufficient size and depth to receive the dowels f^4 , f^5 , and f^{10} . When the pocket is placed in position, lag-screws are inserted 5 through the hollow dowels and firmly secure the pocket in position, the open side being preferably toward the inside of the car. The post or other timber is now placed in position in the pocket and the slide f^7 introduced, 10 after which a common wood-screw is used to secure the slide to the timber in the pocket. Of course it is understood that the timber introduced in the pocket is of the proper length and dimensions to fit snugly in the 15 pocket.

Should it be desired for any reason to remove a timber after it has once been placed in position, it is only necessary to remove the screw which holds the slide in position and 20 take out the slide, when the timber may be readily removed.

The key f^{11} , used in place of the wall f^2 , (see Figs. 11 and 12,) is to enable the timber to be inserted or removed from two sides of the 25 pocket. This is advantageous in the construction of new cars, as it is more convenient to insert the timber from the outside, and after the car is completed and the sidings and the facia in place if it is desired to remove 30 a timber it may be done from the inside. The key f^{11} is really a movable side, sliding in suitable openings in the side walls f^1 and f^3 . One end of this key f^{11} is provided with a 35 flange or bent portion which is approximately at right angles to the key proper and is de-

signed to act as a stop for the inward movement of the key, said bent portion being provided with a suitable hole so positioned as to register with a corresponding hole in the side f^2 , these holes being designed to receive a 40 suitable screw to secure said key in its correct position to the timber.

I am aware that many minor changes in the construction, arrangement, and combination of the several parts of my device can be made 45 and substituted for those herein shown and described without in the least departing from the nature and principle of my invention.

Having thus described my invention, what I claim, and desire to secure by Letters Pat- 50 ent, is—

1. The herein-described timber-pocket comprising a base-plate provided with means of attachment to a timber, side walls formed with seats for a slide, the outer faces of which 55 seats are inclined to force the slide inwardly as it is introduced to crowd or bind the end of the timber in the pocket, and a removable slide, substantially as described.

2. The herein-described timber-pocket comprising a base-plate, dowels rising therefrom, side walls f^1 and f^3 , a slide f^7 and a key or slide f^{11} , substantially as described.

In testimony whereof I hereunto affix my signature, in the presence of two witnesses, 65 this 30th day of November, 1897.

GEORGE S. MARSHALL.

Witnesses:

HUGH K. WAGNER,

F. R. CORNWALL.
